UNITED STATES PATENT OFFICE.

WILLIAM KILLION, OF BOSTON, MASSACHUSETTS.

DESIGN FOR A HORSESHOE-PAD.

SPECIFICATION forming part of Design No. 32,584, dated April 24, 1900.

Application filed March 26, 1900. Serial No. 10,294. Term of patent 14 years.

To all whom it may concern:

Be it known that I, WILLIAM KILLION, a citizen of the United States, residing in Boston, in the county of Suffolk and State of Massachusetts, have invented a new and original Design for Horseshoe-Pads, of which the following is a specification, reference being had to the accompanying drawings, forming part thereof.

- 10 Fig. 1 is a perspective view of my horseshoe-pad, taken from the upper side. Fig. 2 is a perspective view of the same, taken from the under side. Fig. 3 is a side elevation. Fig. 4 is a front elevation.
- 15 As shown in the drawings, the leading or material feature of my design consists of the configuration of the pad formed with the base having forwardly-projecting steps, *a* being the front edge, and *b* the rear edge, both straight and parallel with each other, and *c* forwardly-projecting steps, the inner edges *d* of which are substantially at right angles with the edge *a* and the surfaces being inclined upward toward the rear and the opposite side edges *e* being curved, as shown. The lift or

pad proper, *f*, extends up from the base and has a flat surface, its front edge *h* being substantially at right angles with said surface and parallel with the edge *a*, but at a little to the rear therefrom, so as to produce a ledge *m*. The rear edge *g* of the pad *f* is substantially parallel with the edge *h* and set forward from the edge *b*, so as to produce an edge *n*. The edges or sides of the pad follow the curvatures of the base. The upper corner of the front edge *h* is hollowed out centrally at *k*, so as to form the concave shape shown, and the edge *h* is recessed or notched at its opposite ends, as shown at *l*, and slightly beveled, as illustrated.

Having described my invention, what I claim as new, and desire to secure by Letters Patent, is—

The design for a horseshoe-pad, as herein shown and described.

WILLIAM KILLION.
